UNITED STATES PATENT OFFICE

ERNEST R. HUNTLEY, OF TOLEDO, OHIO, ASSIGNOR TO INDUSTRIAL RESEARCH CORPORATION, OF TOLEDO, OHIO, A CORPORATION OF DELAWARE

FUEL-FEED SYSTEM

Application filed April 12, 1920. Serial No. 373,225.

This invention relates to improvements in liquid feeding systems. While it is capable of more or less general application, the invention is intended primarily for use in connection with internal combustion engines, particularly when employed upon vehicles such as automobiles.

It has been proposed heretofore to employ a diaphragm pump for raising fuel in automobiles, the diaphragm being actuated by various means, for example, by suction impulses transmitted from the engine intake, but in actual practice these pumps have proven inefficient because of the fact that the diaphragms break down after a comparatively short interval of use. This failure I attribute to the rapid vibrating or trembling of the diaphragm, which produces crystallization of the metal and eventual breakage.

One of the principal objects of my invention is to provide a means for actuating a diaphragm pump slowly and without trembling in order to lengthen the life of the diaphragm.

Another object is the provision of means for feeding fuel from a low level tank directly to a high level carburetor.

Another object is the provision of apparatus for pumping two different liquids, such as instance as fuel and lubricant, wherein the pumping impulses are exerted upon one of said liquids and transmitted to the other through a movable wall, preferably a diaphragm.

Another object of the invention is the provision of a fuel pump in which the pumping impulses are produced by a piston moving in a cylinder, but in which the fuel is prevented from coming in contact with the piston and cylinder. This is particularly important for the reason that gasoline is a solvent of lubricating oil and hence it is practically impossible to provide proper lubrication for moving parts with which gasoline comes in contact.

Still another object of the invention is the provision of a fuel feed system taking fuel direct to the carburetor, in which there is a pump operating at a speed proportional to the speed of the engine, but in which the

amount of fuel raised is automatically controlled by the needle valve of the carburetor.

Other objects, and objects relating to details of construction and economies of manufacture will appear as I proceed with the description of that embodiment of the invention, which, for the purposes of the present application, I have illustrated in the accompanying drawings, in which

Figure I is a central, vertical, sectional view through a preferred form of pump.

Fig. II is a view partially in transverse vertical section on the line II—II, Fig. I.

Fig. III is a front elevation of the pump.

Fig. IV is a view principally in horizontal section on the line IV—IV, Fig. III.

Fig. V is a vertical section taken on the line V—V, Fig. IV, and showing in elevation the pump casing on the fuel side of the diaphragm.

Fig. VI is a vertical section taken on the line VI—VI, Fig. I, showing in elevation the pump casing on the oil side of the diaphragm.

Fig. VII is a more or less diagrammatic view showing the preferred form of the invention as applied to use in connection with the engine of an automobile.

Fig. VIII is a central, vertical, sectional view of an oil pump employed in a modified form of the invention.

Fig. IX is a vertical, transverse, sectional view taken substantially on the line IX—IX, Fig. VIII.

Fig. X is a vertical, sectional view showing a fuel pump employed in the modified form of the invention.

Fig. XI is a vertical, transverse, sectional view taken on the line XI—XI, Fig. X.

Fig. XII is a bottom plan view of a structure shown in Fig. X, and

Fig. XIII is a more or less diagrammatic view showing the application of the modified form of the invention to use in connection with the engine of an automobile.

Similar reference characters refer to like parts throughout the views.

Referring first to Figs. I to VII inclusive of the drawings it indicates an internal combustion engine having a carburetor 11 with a fuel intake pipe 12. 13 represents the outer

or front side of a pump casing which is mounted in the side of the engine crank case. 14. 15 is a low level tank from which a pipe 16 leads to the pump. Oil is raised through 5 a pipe 17 from a reservoir in the bottom of the crank case to the rear side of the pump, while it leaves the pump through pipes 18 and 19 which lead it to the parts of the engine needing lubrication.

10 The rear side 20 of the pump casing has centrally thereof a barrel-shaped extension 21 which fits within a perforation in a wall of the crank case 14, the extension being provided with a peripheral flange 22 by means 15 of which attachment to the crank case may be effected, as by means of fastenings 22'. The extension 21 is open at the rear and is bored out centrally to form a cylinder for the reception of a piston 23. The latter is adapted to 20 be driven in one direction by a cam 24 mounted upon a shaft 25 driven from the engine, while its motion in the opposite direction is produced by a coil spring 26 mounted in a cavity in the forward end of the piston and 25 held in position by a guide pin 27, the reduced end of which is driven into the solid portion of the piston. The cam 24, as shown in Figure I, projects as a blunt rounded finger from a sector of the circular cam base of less 30 than 180 degrees circumference, and hence the impulse of the cam is effective during less than half the period of rotation of the cam. The forward end of the cylinder is closed partially in order to provide an abutment 35 against which the spring may bear. A diaphragm 28 is mounted between the front and rear sides 13 and 20 of the pump casing. Both of these sides are slightly concave except at their peripheries. The latter are 40 clamped tightly together by means of machine screws 29 which pass through registering holes in the diaphragm. The diaphragm is thus free to vibrate except at its periphery.

In order to enlarge somewhat the principal 45 path for the movement of oil through the pump the part 20 of the casing has a central vertical groove 30 connecting the pumping cylinder by means of aperture 31 with the oil inlet opening 32 at the bottom and the 50 oil exit passage 33 at the top. The inlet opening 32 connects the groove 30 with a valve chamber 34 in which an upwardly opening ball check 35 is located. The oil pipe 17 is secured to the pump casing below the valve 55 chamber 34 by any suitable means providing a tight joint.

The passage 33 is the first part of the conductor which carries the oil away from the 60 pump to the parts of the engine needing lubrication. Preferably this conductor divides into two branches having two valve chambers 36 and 37 in which are outwardly opening spring pressed ball checks 38 and 39 respectively. From these chambers lead the pipes

18 and 19 with which connection is made by any suitable means.

The fuel raising part of the pump is located upon the opposite side of the diaphragm 28. The front plate 13 of the casing has a central projection in which is formed a passage 40 to a valve chamber 41, in which is mounted an upwardly opening flat check valve 42, the latter being prevented by a depending pin 43 from rising too far off its seat. A suitable connector joins the pipe 16 with the casing below the valve chamber 41. From the point at which the passage 40 opens into the space in front of the diaphragm the front plate 13 of the casing is preferably grooved out slightly to increase the size of the most direct path between the fuel inlet at the center and the fuel exit passage 44 at the top of the pumping chamber. The passage 44 leads to a valve chamber 45 in which is an upwardly opening flat check valve 46 for preventing the backward flow of fuel to the pumping chamber. Pipe 12 extends upwardly from this valve chamber 45.

Now, referring to the modified form of the invention illustrated in Figs. VIII to XIII inclusive, it will be noted that the oil pump alone is mounted on the crank case of the engine and that the diaphragm pump for raising fuel is mounted below the main fuel tank, the diaphragm being actuated by impulses transmitted from the oil pump through a column of oil which extends into a cavity on one side of the diaphragm. The oil pump casing has a rearwardly extending cylinder 50 with a peripheral flange 51 for attachment to the wall of the crank case 14. A piston 23, which may be identical with the corresponding part of the first described form, is driven in one direction by a cam 24 mounted upon a shaft 25 as in the previous case. Return motion of the piston is accomplished by a spring 26 surrounding guide pin 27, which arrangement is also identical with that of Fig. I. The forward end of the cylinder 50 is connected by a short passage 52 with three valve chambers 53, 54 and 55. An upwardly or inwardly opening ball check 56 is located in the chamber 53 and prevents backward flow of oil into the pipe 17. In the chambers 54 and 55 are outwardly opening ball checks 57 and 58 respectively which prevent backward flow of oil into the pump from the pipes 18 and 19 leading to the parts of the engine requiring lubrication.

Through the upper side of the cylinder 50, opposite the short passage 52, is a passage 59. A pipe 60 is secured to the pump casing above this passage. The pipe 60 is of considerable length and is joined at its opposite 125 end to a projection depending from the bottom plate 61 of a diaphragm casing. The bore of the pipe connects with the passages 62 and 63 and thereby with a cavity in the pump casing below a diaphragm 65. The 130

latter is clamped at its periphery between the plate 61 and an upper plate 66, the three parts being secured together firmly and with a liquid tight joint by means of machine screws 67^a. The upper plate 66 includes an enlargement in which are located a horizontal passage 67 and a vertical passage 68. The latter passage runs through an upstanding tubular element which is threaded at its upper end to fit the threads of the socket 69 ordinarily provided in the bottom of the main fuel tank for the accommodation of the drain plug. Above one end of the passage 67 is a valve chamber 70 in which there is an upwardly opening flat check valve 71. In communication with this valve chamber and upon opposite sides of the passage 67 are a pair of vertical passages 72 and 73 which open at their lower ends into a cavity 74 above the diaphragm 65. A short vertical passage 75 connects the cavity 74 with a valve chamber 76 in which is located an upwardly opening flat check valve 77. It will be noted that with relation to the diaphragm, valve 71 opens inwardly and valve 77 outwardly. A connector 78 is threaded into a projection upon the upper plate 66 of the pump casing directly above the valve chamber 76 and to the other extremity of the connector is secured by any suitable means a pipe 79 leading to the carbureter 11.

Operation

In both modifications of my invention operation of the oil circulating means is substantially the same. In both cases movement of the piston 23 to the right (Fig. I and Fig. VIII) by means of the spring 26 exerts a suction impulse permitting atmospheric or other pressure in the crank case 14 to force oil up pipe 17, thereby raising ball check 35 or 56 as the case may be, and on into the space above the valve. Then the movement of the piston towards the left by means of cam 24 forces a certain proportion of the oil above the lower check valve through ball checks 38 and 39 or 57 and 58, as the case may be, through pipes 18 and 19 into the engine bearings, etc., whence it flows back to the reservoir in the bottom of the crank case and is ready to be taken into the pump once more. The circulation of oil is thus continuous, and the quantity pumped is proportional to the speed of the engine. The amount of oil pumped will be affected slightly, although not very materially, by the changing amplitude of vibration of the diaphragm 28. In other words more oil will be pumped when the diaphragm is absolutely still than when it moves back and forth in response to the compression and rarefaction impulses in the oil.

In the structure of Figs. I to VII inclusive the pumping diaphragm is located in the same casing with the reciprocating piston. Now a suction impulse in the oil produced

by the travel of the piston to the right causes the center of the diaphragm also to move to the right, producing a suction impulse in the fuel pumping chamber at the left of the diaphragm. This enables atmospheric pressure above the fuel in the main fuel tank to force fuel up pipe 16, past check valve 42, and through valve chamber 41 and passage 40 into the space above the diaphragm. Then the return movement of the piston causes the oil to push the middle of the diaphragm to the left causing a compression impulse in the fuel pumping chamber which forces fuel through passage 44, past valve 46 and out through pipe 12 to the carbureter. If it be assumed that the carbureter is demanding fuel the diaphragm 28 must move back and forth in response to each pumping impulse in the oil caused by the reciprocation of the piston 23. The extent of this movement will be dependent upon the requirements of the carbureter at the time, that is, when the engine throttle is open and considerable fuel is being taken into the carbureter in proportion to the speed of the engine, then the vibration of the diaphragm will be greater than when the throttle is closed entirely but the engine running, as when an automobile is traveling down hill, there will be no movement whatever of the diaphragm. At such times it is supported as a rigid wall by the fuel in front of it, and although the circulation of oil continues no fuel is pumped. Thus the quantity of fuel raised at all times is controlled automatically by the needle valve of the carbureter. This eliminates any need whatever for an auxiliary or high level tank.

In the structure of Figs. VIII to XIII, inclusive, the operation of the oil pumping part of the apparatus is the same as in the first modification except that the piston pump, in addition to maintaining a constant circulation of oil to the moving parts, also exerts compression and rarefaction impulses alternately upon a column of oil contained in pipe 60. This pipe is full of oil which moves back and forth slightly in response to the force exerted by the piston, except at times when the needle valve of the carbureter is closed and the diaphragm is consequently rigidly cushioned by the fuel in cavity 74. When this condition obtains the full strength of the pumping impulses of the piston 23 is exerted to circulate oil instead of being partially expended in moving the column of oil in the pipe 60. During the operation of the fuel pumping apparatus the movement of the oil beneath the diaphragm 65 causes the latter to move up and down, producing compression and rarefaction impulses in the pumping chamber above. These impulses alternately force fuel up past check valve 77 and through pipe 79 to the carbureter and permit fuel to descend through passages 68 and 67 past

check valve 71 and through passages 72 and 73 into the cavity 74. As in the case of the first modification, the extent of movement of the diaphragm and the consequent amount of fuel pumped are regulated automatically by the needle valve of the carburetor.

It should be understood that although my invention is adapted to be employed without an auxiliary or high level tank for fuel, nevertheless the invention is not necessarily restricted to a system in which the auxiliary tank is omitted.

I am aware that the particular embodiment of my invention above described, and illustrated in the accompanying drawings is susceptible of considerable variation without departing from the spirit thereof, and therefore I wish to claim my invention broadly as well as specifically as indicated by the appended claims.

I claim as my invention:

1. In combination, two liquid feed systems, a pair of chambers one in each of said systems separated by a diaphragm, means for producing a pumping cycle in the liquid in one of said chambers whereby the diaphragm is actuated to produce a similar cycle in the liquid in the other chamber, the impulse time of such cycle being less than the non-impulse time.

2. In a gas engine, the combination of a lubricating oil system, a fuel oil system, a pair of chambers, one in each of said systems separated by a diaphragm, means for producing pumping impulses in the lubricating oil chamber whereby the diaphragm is actuated to produce similar impulses in the fuel oil chamber.

3. In a gas engine, the combination of a lubricating oil system, a fuel oil system, a pair of chambers, one in each of said systems separated by a diaphragm mechanically operated, means for producing pumping impulses in the lubricating oil chamber whereby the diaphragm is actuated to produce similar impulses in the fuel oil chamber.

4. In a gas engine, the combination of a lubricating liquid tank, a distributing system for said lubricating liquid, a fuel liquid tank, a distributing system for said fuel liquid, a casing connected to both distributing systems, a diaphragm in said casing dividing the same into two chambers, one chamber connecting with the lubricating system and the other chamber connecting with the fuel system, and pumping means in the lubricating system chamber, having a cycle with the impulse time less than the non-impulse time including a reciprocable piston adapted to pump a lubricant through the lubricating system and to flex the diaphragm, thereby causing pumping action in the fuel system.

In testimony whereof I affix my signature.

ERNEST R. HUNTLEY.
